(57) **CLAIM**

The ornamental design for a combined handle and strap attachment for a handbag, as shown and described.

DESCRIPTION

FIG. 1 is a perspective view of a combined handle and strap attachment for a handbag, showing the new design.

FIG. 2 is another perspective view thereof.

FIG. 3 is a front elevational view thereof.

FIG. 4 is a back elevational view thereof.

FIG. 5 is a right side elevational view thereof.

FIG. 6 is a left side elevational view thereof.

FIG. 7 is a top plan view thereof; and,

FIG. 8 is a bottom plan view thereof.

The dot-dot-dash broken lines are shown for the purpose of illustrating parts of the article that form no part of the claimed design.

1 Claim, 8 Drawing Sheets
